DESK-TYPE STAPLING MACHINE

Fredrick W. Schmidt, Haworth, N.J., assignor to Markwell Manufacturing Co., Inc., New York, N.Y., a corporation of New York

Filed July 3, 1961, Ser. No. 65,792

Term of patent 14 years

(Cl. D74—1)

FIG. 1

FIG. 2

FIG. 3

FIG. 4

FIG. 1 is a side perspective view of a desk-type stapling machine showing my new design;

FIG. 2 is a top plan view thereof;

FIG. 3 is a side elevational view, the side opposite thereto being substantially similar in appearance; and

FIG. 4 is a front elevational view thereof.

The characteristic feature of my design resides in the combination on the stapler disclosed of the particular knob member which fully encloses the forward end of the arm, substantially as shown.

I claim:

The ornamental design for a desk-type stapling machine, substantially as shown and described.
